UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE.

1,340,488.

Specification of Letters Patent. Patented May 18, 1920.

Application filed December 18, 1916. Serial No. 136,596.

To all whom it may concern:

Be it known that I, ALFRED G. F. KUROWSKI, a subject of the Emperor of Germany, but having taken out United States naturalization papers, residing in Brooklyn borough, in the county of Kings, city and State of New York, have invented certain new and useful Improvements in Typewriting-Machines, of which the following is a specification.

This invention relates to a combined line gage and work-sheet holder, and more especially to one adapted to maintain the same relative position with respect to the platen in both upper and lower-case positions of the latter, and also to handle stiff work-members such as index or show cards.

According to the present invention, where it is desired to write on the extreme bottom of a work-member, such as a show card or index card, it has been found feasible to use the regular line gage in holding the work-member snug on the platen. In order that the combined line gage and holder may shift with the carriage in moving to upper-case position, it is loosely connected to the platen shift frame to move with the latter, as it adjusts the position of the platen. The line gage is guided in its movement at a point comparatively near its holding edge and also at a point distant from the same, so that it will have a substantial rectilinear movement. In order to permit this vertical movement and hold the work-member positively on the platen, the lower guiding means is formed of a roller bearing to minimize the friction. This roller bearing engages in a channel in the supporting mechanism for the line gage, so as to guide and restrain against lateral movement as well as back and forth movement.

While the line gage holds the work-member snug on the platen at the line of writing, it is sometimes necessary with an especially stiff card to prevent the latter from springing away from the platen, by holding it at points above the line of writing. For this purpose, there are provided a pair of holding or guiding fingers which may be used or not, as the circumstances require. They are adjustably mounted on the line gage, so that they can be shifted between concealed inactive positions and ex-

posed active positions. Provision is made for automatically locking the fingers in either position of adjustment.

Other features and advantages will hereinafter appear.

In the accompanying drawings,

Figure 1 is a vertical section taken from front to rear, showing the general relation of the improvement to the typewriting mechanism.

Fig. 2 is a detailed front view and elevation of one of the overhead pressure rollers for maintaining a work-member in engagement with the platen, at a point considerably above the line of writing.

Fig. 3 is a skeleton perspective view showing the case-shift mechanism and the relation of the combined line gage and holder thereto. In this view, the holding fingers are shown in their upright active positions, while the platen and line gage are shown in their lower-case positions.

Fig. 4 is a vertical section from front to rear of the case-shift mechanism, and the combined card holder and a line gage, showing the platen and the line gage in their upper-case positions.

Fig. 5 is a horizontal section on the line 5-5 of Fig. 4, giving an idea of the manner of connecting the plate to the two wings of the line gage and holder.

Fig. 6 is a spread perspective view showing the details of one-half of the combined line gage and work-member holder. The parts being disassembled one from the other, to bring out more clearly their nature.

Fig. 7 is a horizontal section through one of the wing scales and the holding finger connected to the same, showing the holding finger in its depressed inactive position.

Fig. 8 is a front view elevation of the parts shown in Fig. 7. The scale, however, is being but outlined to expose the parts behind the same.

Fig. 9 is a similar view of Fig. 8, except that the finger is raised to its active position.

Fig. 10 is a vertical section through one of the wings of the line gage, showing the holding finger in its depressed inactive position.

Fig. 11 is a view similar to Fig. 10, except that the holding finger is shown raised in

the act of holding a stiff card against springing away from the platen at the line of writing.

Referring more particularly to the specific parts of this invention as embodied in the form shown in the drawings, 1 indicates numeral and alphabet keys, which, when actuated, depress key levers 2, to rock bell cranks 3, to swing type-bars 4 up rearwardly 10 against the front side of a platen 5, mounted to rotate on a platen frame 6. The platen frame 6 is adjustably mounted on a carriage 7, which travels back and forth on a frame 8. The usual escapement mechanism 9, controlled by the keys 1, is used to advance the carriage step by step in letter-feeding direction. The platen frame 6 is adjustable vertically on the carriage 7, so as to admit of a change in printing from lower-case to 15 upper-case characters and back again, the type-bars 4 being provided with two sets of characters 10 and 11 alternatively effective, according to the lower or upper-case positions of the platen.

20 25 In order to adjust the platen between upper- and lower-case positions, there are provided two case-shift keys 12, one active when held depressed, and the other capable of being locked in its depressed position for any desired period. These keys 12, when depressed, rock key levers 13, to swing forward arms 14 thereon, so that the latter will rock a shift frame 15 forwardly and upwardly. The shift frame 15 is provided 20 with a shift rail 16, on which rest rollers 17 carried by the platen frame 6. The platen frame 6 is further guided in its vertical movement by arms 18 pivoted at 19 and engaging pins 20 on the platen frame 30 35 40 45 6. The pins 20 and the rollers 17 are so located that they will cause a substantially vertical movement of the platen 5, or, at least, such that the cylindrical element forming the line of printing, in any particular instance will move to an upper-case position, substantially superposed above its lower-case position.

In order that the typewriting may be justified, both as to the line of writing and 50 along the line of writing, there is provided a line gage 21, which includes a pair of wing scales 22 spaced apart from each other, to admit of the type-bars 4 striking the work-sheet between them. These wings are 55 provided with scales at their upper edges, to measure the position of the typewriting along the line of writing.

The line gage 21 may also serve the function of holding a work-member snug on the 60 platen at the line of writing. To do this, the wings 22 are adjustably mounted on a common member and spring-held with their edges in snug engagement with the surface of the platen. This mounting includes a 65 pair of supporting plates 23, united inte-

grally with each other by means of a cross-bar 24, so as to form a unitary supporting member. It will be noted in passing that the cross-bar 24 is provided with a rectilinear dip rearwardly to allow room for 70 movement of the ribbon-vibrating mechanism. To mount the wings 22, the plates 23 are bent rectilinearly forwardly and upwardly to form brackets 25. Each of these brackets is provided with a cut-away portion, 75 having on the sides thereof, rearwardly-extending lugs 26, apertured to form bearings for a pin 27. The pin 27 pivots a hinge 28, in each instance, to the corresponding bracket 25. On each of the hinges 28, is mounted 80 one of the wings 22 by means of screws 29. The upper parts of the wings 22 are bent inwardly to clear the brackets 25 and engage the platen. The wings 22 are held yieldingly in engagement with the platen 85 by means of spiral springs 30, wound around the pins 27 and engaging the brackets 25 at one end, and the hinges 28 at their other end.

Thus, a spring hinge mounting for each 90 of the wings 22 is provided, which, while it will maintain a certain amount of pressure sufficient to hold the work-member on the platen, will yield in case any part of the typewriting mechanism on the carriage 95 engages the same during an extreme traveling movement of the carriage. The ends of the wings 22 are dished outwardly for this purpose. To limit, however, the movement of the wings toward the platen, under the 100 impulse of their springs 30, they are engaged by stops 31, one on each of the brackets 25.

The wings 22, forming the line gage in many cases, are sufficient to supplement the 105 usual pressure rollers 32 in holding the work-member snug on the platen. In some cases, however, where especially stiff cards are being written on, it is desirable to warp them to the platen for at least the full height 110 of the written characters, by holding them at a point somewhat above the line of writing. For this purpose, there are provided holding and guiding fingers 33, one for each wing and separated from each other 115 a sufficient distance, to balance the holding or guiding action. The fingers 33 are pivotally mounted on the brackets 25 in the rear thereof, so as to be swung from a depressed inactive position (Figs. 8 and 10), 120 to a raised active position (Figs. 9 and 11).

The fingers are shifted from one position to the other, by providing each of them with a shifting lever 34, pivotally mounted at 125 35 on the opposite side of the bracket to the finger. Each lever 34 is provided with a pin 36, extending through a slot 37 into engagement with a cam slot 38, provided in the corresponding finger 33. The cam slot 38 is so formed, that when the lever 34 130

is in a depressed position (Figs. 6 and 8), the finger 33 will likewise be in a depressed inactive position. When, however, the lever 34 is moved from the position of Fig. 8 to 5 the position of Fig. 9, the pin 36 will cam up the finger 33 until it reaches a substantially vertical position. Considering the finger 33 in its work position, the upper end of the cam slot 38 has its surfaces substantially concentric with the pivotal axis 35 of the lever 34, so that the finger 33 cannot be accidentally depressed, as it would act on the pin 36 perpendicularly to the arc 10 of movement of this pin. The lever 34 is 15 adjusted by means of a handle or finger-piece 39, which extends through a slot 40 in the corresponding wing 22. The lever 34 is yieldingly locked in its two positions of adjustment by means of a spring latch 20 41 having a pin 42 passing through the lever and extending alternatively into a pair of openings 43 and 44 provided in the associated bracket 25.

The two fingers 33 swing oppositely to 25 each other so as to move toward each other when coming to operative position and away from each other when moving down in a concealed inactive position. The inner upper corners of the wings 22 are bent upwardly at 45 to enable the fingers to clear the wings, whereby they may be in action close to the platen at the same time the fingers are. The upper ends of the fingers are spoon-shaped so as to form an anti-friction engagement with the work-member 30 on the platen.

In order that the gage and fingers may be just as effective in the upper-case position of the platen as in the lower-case, they are 40 mounted so as to shift vertically at the same time that the platen shifts. To do this, the unitary supporting member 23, 24, is connected to be moved by the case-shift frame 15. Joined to the supporting member 23, 24, 45 there is provided a slide 46 forked at its upper end to be rigidly connected to the supporting plates 23 so as to practically form a part of the supporting member. The upper ends of the tines of the fork are 50 warped forwardly and the body of the slide itself is warped rearwardly to form a V bend which avoids the type actions. This latter also forms supporting surface for a bracket 47 to which is pivotally connected a 55 link 48. The latter is also pivotally connected to a bracket 49, mounted on the shift rail 16. This forms a flexible connection of the slide, to the shift frame 15, so that when the latter is actuated by the shift keys 60 12 to change the platen from lower to upper-case position, the line gage and holder with the guiding fingers 33 will also be moved vertically substantially the same amount as the cylindrical element at the 65 line of writing on the platen moves, so that

the line gage and other parts will maintain the same relation to the platen.

The slide 46, however, is guided so that its movement will be rectilinear instead of arcuate, like the shift frame 15. This is 70 accomplished at the upper end, by a guide 50 which forces the supporting member 23, 24, into engagement with the back face of a segment 51 on which the type-bars 4 are mounted. Lateral movement at the upper 75 end is prevented by the guide 50 extending forwardly at its sides, as seen at 52 in Fig. 5, to engage the side edges of the supporting plates 23. Other guiding means includes the slide 46 which is in the form of a single 80 channel member 53 at its lower end. This channel member slides vertically between a rib 54 and an anti-friction roller 55 engaging in the channel of the members. Inasmuch as the pressure on the upper edge 85 of the line gage and on the fingers 33, tends to move the lower end 53 of the slide 46 rearwardly, the roller 55 acts as a guide preventing such movement and minimizes the friction incident thereto. In view of 90 the fact that the member 53 is channeled, it may also engage the sides of the roller 55 preventing lateral movement of the slide 46 and the parts carried thereby.

The sides of the carriage frame have been 95 cut away and reconstructed as indicated at 56 to allow for a relative traveling movement between the carriage and the wing scales 22 when the latter are in their upper-case positions. This is more particularly 100 described and claimed in my co-pending application Serial No. 104,678, filed June 20, 1916 (now Patent No. 1,248,346, dated November 27, 1917).

The overhead pressure rollers 57 are also 105 shifted upwardly from their former position to clear the fingers 33. These rollers are pivotally mounted on spring guides 58, which, in turn are mounted separately on brackets 59. The brackets 59 are adjustably mounted on a rod 60, and each includes a rectilinear piece 61 having key-shaped openings 62 in the ends thereof, through which the rod extends, and also an angle iron 63 projecting forwardly and inwardly 110 from the rod 60. The brackets are locked in an adjustable position by friction springs 64 mounted on the brackets and engaging the rod 60.

When the fingers 33 are in their depressed 120 position, the wings 22, as stated above, yield outwardly against the tension of the springs 30. In order that the card may be held tightly on the platen when the fingers are raised, this outward movement is prevented 125 by a bend 65 (Figs. 10 and 11) in the lever 34 engaging in front of a tongue 66, extending inwardly from the top of the slot 40. This locks each of the wings to the associated supporting plate 23.

It will thus be seen that there is provided a combined line gage and work-member holder with auxiliary holding fingers adaptable for use with various kinds of work-members, and conforming in vertical position with the position of the platen so as to properly coöperate therewith in both upper and lower-case typewriting.

Variations may be resorted to within the scope of the invention, and portions of the improvements may be used without others.

Having thus described my invention, I claim:

1. The combination with a platen shiftable between upper and lower-case positions, of a line-gage shiftable to keep pace with the case-shift movements of the platen, a plurality of fingers adapted to coöperate with a work-sheet, and movable upon the line-gage between operative and inoperative positions, and adjustable with the line-gage to keep pace with the movements of the platen, and a manually-operable finger-piece for each finger also mounted on said line-gage, each connected to its finger and movable to one position to elevate it and to another position to depress it, and adapted to hold it in either position.

2. The combination with a platen, of a line gage coöperating with said platen, of a finger pivotally mounted on said line gage to coöperate with the work-member on the platen, a lever for shifting said finger between operative and inoperative positions, a pin-and-cam-slot operating connection between said lever and said finger, and a dwell in said cam forming a lock to prevent accidental movement of the finger by acting back on the lever when the finger is in its effective position.

3. The combination with a platen, of a wing scale coöperating with said platen, a normally-concealed finger for coöperating with the work-member on the platen, and means operable from a position in front of the wing scale, to shift said finger from its concealed position behind the wing scale to a projected active position.

4. The combination with a supporting bracket in juxtaposition to said platen, of a finger pivotally mounted on said supporting bracket to hold a work-member on said platen, a horizontally disposed finger-piece pivotally mounted on said bracket, and a pin-and-cam-slot connection between said finger and said finger-piece adapted to cause said finger-piece to shift said finger back and forth between a horizontal inactive and a vertical active position.

5. The combination with a platen, of a paper-holding finger coöperating with said platen, a bracket on one side of which said finger is mounted, a lever for operating said finger mounted on the opposite side of said bracket, said finger having a cam slot there-

in, said bracket having a slot therein, and a pin on said lever projecting through said slot into said cam slot so that said finger on the back of said bracket may be operated by said lever on the front of said bracket. 70

6. The combination with a platen, of a bracket in front of said platen, a pair of lugs on one side of a cut-out portion on said bracket, a hinge extending between said lugs, a spring connected to said hinge, a wing mounted on said hinge and bent in toward said platen to be forced into engagement therewith by said spring, a similar pair of lugs on the opposite side of said cut-out portion, and a separate hinge, spring and wing mounted thereon. 75

7. The combination with a platen, of a bracket mounted in juxtaposition to said platen, a paper-holding finger mechanism adjustably mounted on said bracket, and a wing scale covering said mechanism and bent in to clear said mechanism and said bracket so as to engage the platen. 80

8. The combination with a platen, of a bracket mounted in juxtaposition to said platen, a wing mounted on said bracket, a work-member-engaging finger adjustably mounted on said bracket, and a lever mechanism for adjusting said finger, located between said bracket and said wing and having a handle projecting through said wing to be operated from the front of said wing. 95

9. The combination with a platen, of a wing scale coöperating with said platen, a work-member-engaging finger in back of said wing scale, and mechanism for operating said finger having a handle projecting through said wing scale to be operated from the front of said wing scale. 100

10. The combination with a platen, of a line gage and holder coöperating with said platen, a floating support for said line gage, means for adjusting said platen and said line gage simultaneously for upper and lower-case writing, a two-way guide for said support adjacent the top thereof, and a partly enveloped two-way guide at the bottom of said support. 105

11. The combination with a platen, of a case-shift frame for said platen, a gage to coöperate with said platen in both upper and lower-case positions, a floating support for said gage, a flexible connection from said case-shift frame to said floating support, and guides for said floating support located above and below said connection to said case-shift frame so as to cause a substantially vertical movement of said gage equal in amount to the movement of said platen. 115

12. The combination with a platen, of a case-shift frame for said platen, a gage coöperating with said platen, a floating support for said gage, a flexible connection from said case-shift frame to said support ena- 120

bling the concomitant movement of said gage with said platen between lower and upper-case positions, said support having a channel formed therein, and a roller guide 5 engaged in said channel to limit the lateral travels of said support on said gage while permitting anti-friction vertical movements of said support.

13. The combination with a platen shift-
10 able between upper and lower-case positions, of a line gage and holder coöperating with said platen, a floating frame for said line gage enabling vertical movements with the vertical movements of the platen, and an 15 anti-friction roller guide for said support.

14. The combination with a platen, of a line gage and holder coöperating with said platen, a case-shift frame for said platen, a floating support for said line gage, a flexible 20 connection between said shift frame and said floating support, a two-way guide for said support above the flexible connection, and a rib and roller guide engaging said support below the flexible connection.

25 15. The combination with a platen, of a work member holder coöperating with said platen, a case-shift frame for adjusting said platen and said holder concomitantly between lower and upper-case positions, a support 30 for said holder having a V-bend therein, a link connected to said support at the V-bend and to said shift frame, and sliding guiding means for said support below said V-bend.

35 16. The combination with a platen, of a wing for resiliently coöperating with the platen, a finger adjustably mounted relatively to said wing, means for shifting said finger to cause it to coöperate with said 40 platen to maintain a work-member properly on said platen, and means associated with said shifting means for automatically locking said wing against movement away from said platen.

45 17. The combination with a platen, of a wing for resiliently coöperating with said platen, a finger adapted to coöperate with said platen to properly maintain a work-member on said platen, shifting means for 50 moving said finger between operative and inoperative position, and locking means operated by said shifting means adapted to automatically lock said wing against move-

ment away from said platen when said finger is in its active position. 55

18. The combination with a platen, of a wing coöperating with said platen, a yielding mounting for said wing enabling it to swing transversely away with respect to said platen, a finger coöperating with said platen pivotally mounted to move between active and inactive positions relative to said platen, shifting means for said finger having a bend therein, and a tongue on said wing engaging in said bend when said finger is in its effective position, so as to lock said wing against spreading movement relative to said platen.

19. The combination with a platen, of a wing adapted to coöperate with said platen, 70 a resilient mounting for said wing adapted to hold it against said platen along one edge thereof, a locking arm lying between the wing and the platen, a lug on said wing adapted to be engaged by said arm to lock 75 the wing against the platen, a finger-piece extending from said arm in front of said wing adapted to enable the typist to shift said arm to locking or non-locking position, and a paper-guiding finger moved to working 80 position by said finger-piece when said arm is moved to locking position.

20. The combination with a platen, of a wing adapted to coöperate with said platen, 85 resilient means to hold the wing against said platen, a locking means for said wing, a finger-piece to shift said locking means to locking position, and a paper-guide connected to said finger-piece to be moved to working position when said wing is locked. 90

21. The combination with a revoluble platen mounted for case-shifting, of a card or paper guide movable from non-working to working position in front of said platen, a resilient support for the guide shifting 95 with the platen, a lock for said support ineffective when said card guide is in non-working position, and means connected to said card guide and said lock to move the card guide to working position and simultaneously make said lock effective, to hold 100 the support against resilient yielding.

ALFRED G. F. KUROWSKI.
